UNITED STATES PATENT OFFICE.

JOHN MILNE, OF BROOKLYN, NEW YORK, ASSIGNOR TO MILNE BOILER CO.,
A CORPORATION OF NEW YORK.

COMBINED STEAM-GENERATOR AND STEAM-SUPERHEATER.

SPECIFICATION forming part of Letters Patent No. 772,315, dated October 11, 1904.

Application filed April 18, 1903. Serial No. 153,151. (No model.)

To all whom it may concern:

- Be it known that I, JOHN MILNE, a citizen of the United States of America, and a resident of the borough of Brooklyn, county of 5 Kings, State of New York, have invented certain new and useful Improvements in a Combined Steam-Generator and Steam-Superheater, of which the following is a specification.
- 10 This invention relates to steam-generating apparatus, and has for its object the production of a steam generator or boiler which has connected therewith a steam-superheater, the latter being subjected to the hot gases and 15 products of combustion.
- Figure 1 represents a partial vertical section of my invention as on the line $x-x$ of Fig. 3. Fig. 2 shows a plan view of a fragmentary portion of Fig. 1. Fig. 3 is a partial 20 front view and sections of Fig. 1 on the lines x', x^2 , and x^3 .
- The invention is represented to consist of the upper drum A, from which extend steam-generating tubes B, the latter connecting with 25 a lower drum C. Baffle-plates B' extend upwardly from the lower drum, and baffle-plates B² extend downwardly from the upper drum A. Tubes or pipes D extend from the lower drum C and are capped by a manifold or 30 header E, which latter is independent of and not connected with the drum A, its interior being isolated therefrom. Hand-hole caps E' are secured in the header E to allow the cleaning of the tubes D and their removal for the 35 insertion of new tubes. The said tubes D, with the header E, constitute an economizer.
- To secure a superheater, two independent manifolds or headers F F' are connected with tubes or pipes F², and an outlet is provided 40 in the said top header at F³. The upper header F' has its interior isolated from the upper drum, and the lower header F is connected with the lower drum C by means of piping H, in which latter there is fitted the valve H, the 45 said piping being used to flood the superheater.
- Steam-outlet pipes are shown at I, having the safety-valves I' and horizontal connecting
- branch pipes I², with the valves I³ and the T 50 I⁴. From the horizontal pipes I² there extend the vertical pipes J, having the valves J' and connecting with the header F.
- The drums A and C, with their tubes B, the header E, with its tubes D, and the tubes F², with their headers F and F', are inclosed 55 by the rear wall K, front wall G, side walls L, top covering M, and bottom N, forming a chamber for the steam-generating apparatus.
- The furnace is shown at O, with its grates P, furnace-door R, and ash-pit door R'. The 60 crown S of the furnace is connected with the wall S', that supports the header F and forms a portion of the front of the boiler. An iron front T is represented with movable panels T'.
- Buck-staves U are located at the rear of the 65 generator, and buck-staves U' are attached at the sides.
- V is an outlet for the connection with the chimney, and cleaning-doors V' V² are located in the side walls of the boiler. A blow-off W is connected with the lower drum C. 70
- When using my steam-generating apparatus, the gases and products of combustion on leaving the furnace O pass around and about the portion of the steam-generating tubes B in front of the baffle-plate B' and also pass around and about the tubes F² of the steam-superheater. They ascend to the drum A and then descend, circulating about the tubes between the baffle-plates B' and B² and from 75 thence pass upwardly around and about the tubes B back of the baffle-plates B² and also about the tubes D of the economizer, after 80 which they enter the chimney through the opening V. Superheated steam is obtained 85 at the outlet F³, and should it be desired not to use the steam-superheater the valves J' are closed and the valves I³ opened, when the steam can be taken from the outlet of the T I⁴; and at the same time the valve h in the 90 piping H is kept open to flood the superheater tubes or pipes F² to protect them from the hot gases of combustion. The construction is such that, if desirable, the entire superheater can be removed after the valves J' are 95 closed. When the steam-superheater is used,

the valves I^3 are closed, and it is evident that, if desirable, steam can be supplied both from the T I^4 and from the outlet F^3 .

Having described my invention, I claim—

5 1. In a steam-superheater the combination of piping extending from a steam-supply, a branch pipe extending from said piping, a valve in said branch pipe, a valve in the piping beyond its connection with the branch pipe, a header connected with the end of the piping, steam-superheating tubes extending from the header, piping for water connected to the header, a valve in the latter piping, and an independent header capping the steam-
10 superheating tubes.

15 2. In a steam - generating apparatus and steam-superheater, the combination of an upper and a lower drum, a chamber inclosing the said drums, tubes connecting the drums,

steam-piping extending downwardly from the upper drum and outside of the said chamber, a header connected with the lower end of the steam-piping, steam-superheating tubes on the inside of the chamber and connected with the said header, piping on the outside of the chamber extending between the said header and the lower drum, a second header isolated from the upper drum capping the steam-superheating tubes, and having an outlet therefrom on the outside of the steam-generating apparatus.

Signed at New York, county and State of New York, this 17th day of April, 1903.

JOHN MILNE.
